UNITED STATES PATENT OFFICE

156,323

FLOWER POT HOLDER OR SIMILAR ARTICLE

Isabel V. Dahlquist, Middletown, Conn.

Application June 9, 1948, Serial No. 146,843

Term of patent 3½ years

(Cl. D35—3)

To all whom it may concern:

Be it known that I, Isabel V. Dahlquist, a citizen of the United States, residing at Middletown, in the county of Middlesex and State of Connecticut, have invented a new, original, and ornamental Design for a Flower Pot Holder or Similar Article, of which the following is a specification, reference being had to the accompanying drawing, forming part thereof.

Fig. 1 is a perspective view of a flower pot holder or similar article showing my new design; and

Fig. 2 is a front view of the same.

The broken lines shown in Fig. 2 are for illustrative purpose only.

I claim:

The ornamental design for a flower pot holder or similar article, substantially as shown and described.

ISABEL V. DAHLQUIST.
